STRAIN INSULATOR CLEVIS

John Brown Cook, Chicago, Ill., assignor to Reliable Electric Company, Chicago, Ill., a corporation of Illinois

Application September 18, 1939, Serial No. 295,475

4 Claims. (Cl. 248—65)

The present invention relates to means for anchoring a strain insulator or the like to a mechanical load carrying member such as a cross arm of a transmission pole. It is particularly concerned with what sometimes is called in the trade a "dead end strain insulator clevis." My improved clevis utilizes a tension member adapted to be threaded through a strain insulator or similar device attached to the wire or cable sought to be anchored. The tension member is provided at its ends with heads designed to enter into engagement with a cooperating device which is mounted on the load carrying member. The present invention contemplates a cooperating device which provides for ready attachment and release of the headed tension member, hereinafter referred to as a wire, without disturbing the mounting of the device. Preferably, said device comprises spaced slotted portions extending away from the load carrying member on which it is mounted with flanges on said portions provided with slots to receive the wire and to prevent passage of the heads of the wire. The strain from the strain insulator or the like is carried by the length of wire to the heads thereof and is transferred to the anchoring device by means of the heads bearing on the flanges.

The purpose of the present invention is to provide an improved connecting device between the strain insulator or the like and the load carrying member. It is desirable to minimize the number of parts necessary in a device of this character and to provide means for hooking the length of wire in place after the clevis is mounted in position. This latter feature permits replacement of the strain insulator without having to remove the clevis and any other equipment mounted at the other end of the bolt fixing the clevis to the cross arm or load carrying member. It is also desirable to provide a latitude in the angle of take-off that the device will accommodate and yet retain the maximum load carrying strength. Applicant's invention provides these features and advantages in a device characterized by simplicity and ease of manufacture.

The features and advantages of the present invention will appear more fully as the description proceeds, reference being had to the accompanying drawing wherein a preferred form of the invention is shown. It is to be understood, however, that the drawing and description are illustrative only, and are not to be taken as limiting the invention except insofar as it is limited by the claims.

In the drawing,

Fig. 1 is a side elevation illustrating the clevis assembly connecting a dead end clamp and strain insulator to a cross arm;

Fig. 2 is a top view of the clevis assembly showing the method of connecting the length of wire to the clevis;

Fig. 3 is a view showing the slotted flanges, and

Fig. 4 is a view illustrating the mounted clevis showing a large take-off angle.

Referring now in detail to the drawing, the present invention is directed toward a dead end strain insulator clevis by which a wire or cable 10 may be anchored to a load carrying member 21. In carrying out the present invention, the wire 10 is gripped in a dead end clamping device 11 which is threaded through a strain insulator or the like 12. Also threaded through the strain insulator or the like 12 is a length or strand of wire or other suitable material 13, the ends of which are provided with heads 14 and 15. The heads 14 and 15 are of such size that they may be readily threaded through the openings 34 and 35 provided in the clevis member as hereinafter described.

The heads 14 and 15 may be provided on the length of wire 13 in any suitable fashion. In the present invention they are shown as tubes of metal which are compressed on the wire 13 by applying pressure to the opposite sides thereof at points 16 and 17 by which the metal of the tube is forced inwardly to deform the wire 13 and thus permanently unite the tubes 14 and 15 with the wire 13.

To receive and hold the wire 13 a cooperating device 20 is provided. Said cooperating device 20 is mounted on the load carrying member 21, which is shown in the drawing as a cross arm fixed to a pole 22. In the preferred embodiment of the invention, the cooperating device 20 is mounted on the load carrying member 21 by means of a bolt 23 passing through a hole 24 in the cooperating device 20 and a hole through the member 21. The bolt 23 is fitted with a nut 25. Extending away from the portion of the cooperating device 20 adjacent to the load carrying member 21 are spaced portions 30 and 31, and extending therefrom are curved flanges 32 and 33.

The spaced portions 30 and 31 are provided with slots or openings 34 and 35 somewhat removed from the flanges 32 and 33. Said slots or openings 34 and 35 are of an appropriate size to permit the heads 14 and 15 on the wire 13 to readily pass therethrough. Extending away from the slots 34 and 35 are slots 36 and 37. Said

slots 36 and 37 extend into the flanges 32 and 33, respectively, and are of a width to permit the passage of the wire 13. Connecting to slots 36 and 37 in the flanges 32 and 33 are slots 38 and 39. Said slots 38 and 39 extend throughout a portion of the length of the flanges 32 and 33 and are of a width sufficient to permit the passage of the wire 13 and to refuse passage to the heads 14 and 15 on the wire 13.

To assemble the length of wire 13 with the cooperating device 20, heads 14 and 15 on the wire 13 are respectively passed through the slots 34 and 35 in the spaced portions 30 and 31. At the same time, the wire 13 enters the slots 38 and 39 in the flanges 32 and 33 through the connecting slots 36 and 37. As thus assembled, the heads 14 and 15 bear on the flanges 32 and 33, the wire 13 passing through the slots 38 and 39 and around the strain insulator 12.

It is to be noted particularly that in the principal form of the invention the flanges 32 and 33 are longitudinally curved throughout their length. The purpose of this curve is two-fold. The slots 36 and 37 entering the flanges 32 and 33 are so related to the curve that the portion of the flange at the slots 36 and 37 will never be used for bearing surfaces for the heads 14 and 15. This construction permits a maximum bearing surface for the heads 14 and 15, regardless of the position of the wire 13 in the slots 38 and 39. In other words, the portions of the flanges weakened by the entrance slots 36 and 37 will never be used for bearing. The curve of the slotted flanges 32 and 33 permits the use of any angle of take-off within the limit set by the degree of curve and length of the flange. The maximum strength of the device is maintained at any angle of take-off as the heads 14 and 15 bear fully on the flange regardless of the angle used.

As a variation of the above described form of the invention, it may be desirable to provide the means for attaching or detaching the length of wire at one of its ends only. This could be accomplished by, for example, eliminating slot 34 and slot 36 from the spaced portion 30. The wire 13 would necessarily be threaded through slot 38 before the heads 14 and 15 were fixed on the wire.

It will be readily apparent from the foregoing description that I have provided a simple, economical and highly convenient clevis of the character described.

From the foregoing description it is believed that the construction and operation of the present device will be readily apparent to those skilled in this art. Having thus described my invention, what I claim as new and desire to secure by Letters Patent is:

1. A clevis of the character described comprising a length of wire having enlarged heads at both ends and a mountable cooperating device to receive said wire, said cooperating device comprising spaced portions having slots therein and flanges extending laterally therefrom, said flanges having elongated longitudinally running slots

therein communicating with the slots in said spaced portions, the slots in said spaced portions being of appropriate size to permit passage of the enlarged heads of the wire therethrough, the slots in said flanges being of a width greater than the diameter of the wire but less than the width of the heads at the ends thereof, said flanges being longitudinally curved substantially throughout their length so the take-off angle of the wire can be changed.

2. A clevis of the character described comprising a tension member having enlarged heads at both ends, a mounting device for said tension member comprising a substantially flat base and spaced, substantially parallel, plate portions projecting from said base, curved flanges at the free edges of said parallel portions opposite the base, said flanges extending substantially at right angles to said spaced portions, said parallel portions having slots large enough to receive said heads extending toward said flanges, and said flanges having slots running lengthwise thereof along the curve, the last named slots being too small for the heads and large enough to receive the tension member, one end of each of the flange slots being connected to the enlarged slots in said spaced portions by an intermediate slot large enough to pass the tension member but too small for the heads thereon.

3. A clevis comprising a mountable member including a web portion adapted to be secured to a load carrying member, spaced tension member attaching portions extending in the same general direction from said web, a tension member, at least one of said portions having a lateral flange extending from the free end thereof, said portion and said flange having slots therethrough, and a slot connecting the slot in the flange to the slot in the spaced portion, the slot in the flange extending lengthwise thereof in spaced relation to the adjacent wall of the portion to which it is attached and being spaced from the free edge of said flange throughout its extent, said tension member having an enlarged head, the slot in said spaced portion being sufficiently large to pass the enlarged head on said tension member, the slot in said flange and the connecting slot being sufficiently large to pass the tension member, but too small for the head thereon.

4. A clevis comprising a mountable member including a web portion adapted to be secured to a load carrying member, spaced portions extending in the same direction from said web, at least one of said portions having a slot therethrough, lateral longitudinally curved flanges extending from the free ends of said spaced portions, said flanges having longitudinal slots therethrough, slots connecting the slot in a flange to the slot in a spaced portion, and a tension member having enlarged heads at both ends, the slot in a spaced portion being sufficiently large to pass an enlarged head on said tension member, the slot in a flange and the connecting slot being sufficiently large to pass the tension member, but too small for the heads thereon.

JOHN BROWN COOK.
